UNITED STATES PATENT OFFICE.

FREDERICK ROETTGES, OF STAMFORD, CONNECTICUT, ASSIGNOR TO S. ROBERT SCHWARTZ, OF NEW YORK, N. Y.

DESIGN FOR A PORTABLE LAMP STANDARD.

Application filed March 24, 1923. Serial No. 5,577. Term of patent 3½ years.

To all whom it may concern:

Be it known that I, FREDERICK ROETTGES, a citizen of the German Republic, residing at Stamford, county of Fairfield, and State of Connecticut, have invented a new, original, and ornamental Design for Portable Lamp Standards, of which the following is a specification, reference being had to the accompanying drawing, forming part thereof.

The figure is a perspective view of a portable lamp standard, showing my new design.

I claim:

The ornamental design for a portable lamp standard, as shown.

In testimony whereof I have signed my name to this specification this 8th day of January 1923.

FREDERICK ROETTGES.
